LADY'S COLLAR

Filed Nov. 4, 1930

INVENTOR

Georges Ezbelent

BY

Wm. Wallace White

ATTORNEY

UNITED STATES PATENT OFFICE

GEORGES EZBELENT, OF PARIS, FRANCE

DESIGN FOR A LADY'S COLLAR

Application filed November 4, 1930, Serial No. 37,528, and in France July 8, 1930. Term of patent 14 years.

To all whom it may concern:

Be it known that I, GEORGES EZBELENT, a citizen of the Republic of France, residing at 80, rue de Belleville, Paris, France, have invented a new, original, and ornamental Design for Ladies' Collars, of which the following is a specification, reference being had to the accompanying drawing, which is a plan view of a lady's collar showing my new design, which is attained by first plaiting the entire collar with narrow flat folds running longitudinally of the collar, and then form-

ing in a restricted area at the central upper edge of the collar accordion folds, over, and at right-angles to, the said narrow flat folds, the design thus consisting essentially of the novel contrasting areas of single plaiting and double plaiting as shown.

I claim:

The ornamental design for a lady's collar, as shown and described.

In testimony whereof I have signed my name to this specification.

GEORGES EZBELENT.
